POUCH

William Edwards Baxter, Floyd County, Ind.

Application July 30, 1935, Serial No. 33,877

6 Claims. (Cl. 206—41)

My invention relates to a compartment pouch primarily for carrying pipe, tobaccos (smoking, chewing and snuffing, as may be desired), combined pipe-stem and bowl cleaning rod, cigars, 5 cigarettes, matches and match-scratch pad in convenient, unique and sanitary separation, form in combination securely and separately under its coverage and protection several articles of relative usefulness or pleasure, or both, for ready use 10 capable for effective service under various conditions.

A further object of my invention is to provide a compartment pouch to fit the pocket, in profitable purchase and purpose, and one that can be 15 strongly, compactly and economically constructed to meet requirements.

There are many uses for which the said pouch, in accordance with this invention, is admirably and conveniently adaptable, i. e., one, for instance, for use as a vanity pouch the compartments and combination of which are ideal for carrying several articles of the toilet as well as cigarettes, a modern lighter or other means; another instance, use as a handy, safe and convenient pocket, compartment pouch for carrying certain surgical instruments, accessories as well as convenient spoon, scratch-pad and matches for the warming of morphine and other solutions for immediate hypodermic injections.

With the foregoing and other objects in view, the invention consists of novel construction, combination and arrangement of parts as are referred to or as illustrated in the accompanying drawings wherein are shown embodiments of the invention but it is to be understood that changes, 35 variations and modifications may be resorted to which fall within the scope of the invention mentioned in the specification, or shown in the drawings:—

Figure 1 is a plan view of the foundation, or 40 back, part A of the pouch showing the made perforations through its ends portion, and with the smaller dotted lines indicating positions for placement thereon of the front part B, and the larger dotted lines indicative for the inner commencement lines of the flap or folds of part A.

Figure 2 is a plan view of the part B of the 45 pouch showing the made perforations through its body texture; and with the dotted lines indicative of the inner commencement lines of the flap folds of part B; and showing a cylindrical strip of material attached upon one flap of part B.

Figure 3 is a plan view of part C having within 50 the bounds of its face an oblong, circumscribed opening.

Figure 4 shows a plan view of part A with parts B and C superimposed thereon, and the separation into compartments shown by dots indicating stitching, or fastening, as between parts A and B and between parts A and C, also shows the studs as attached to part B and the relative female clasps to part A. 5

Figure 5 is an enlarged side view of the fold over, surface contacting flaps of the parts A and B. 10

Figure 6 is a view similar to Figure 5 with the addition thereto of the hollow, cylindrical strip of material shown attached to or integrally as a part of the flap B⁴ of the part B and partly compressed as within the overlying and thereon 15 pressing folds of the flaps of parts A and B.

Figure 7 is a plan view of part F.

Figure 8 is a plan view of the accessory part D of the pouch showing notched corners of the part D and the large circular perforations 20 through its body texture and its upper and lower semi-stiff edges, as beyond the notched corners.

Figure 9 is a plan view of Figure 4 showing part D superimposed in operative position thereon. 25

Figure 10 is a plan view of part E showing its handle like extensions or tabs.

Figure 11 is a plan view of the pouch showing the flaps as folded over thereon, their contacting surfaces intimately connected throughout by 30 pressure of my applied interlocked or closed relation.

Figure 12 is an enlarged sectional view of the fold over, pouch closure contacting flaps of parts A and B, showing the plan of the semi-stiff ends 35 edges of the part D exerting a definite and sustained pressure outward as against the inward pressure of the aforesaid pouch closure flaps, as along the sectional line 12—12 of Figure 11.

The compartment pouch in its simplicity can 40 be cut, blanked and punched and formed of one piece of material, or of two equal parts cut or blanked and punched by the use of one die and then arranged with one part placed upon the other in such a manner that each end part as 45 extended beyond its opposite relative end will furnish the large flap of a pouch end and its opposite relative end furnished the small flap; when the pouch is made in the foregoing manner the flaps at one end will fold in opposite direction from the folding of the flaps of the opposite end in the act of closing the pouch. 50

When made as follows both ends will have the same appearance when closed (see Figure 11):— Referring to the drawings, I prefer to make the 55

pouch by using two or more pieces of material, preferably of leather or closely woven material of proper thinness and strength, pliable but somewhat resilient so when the pouch's end flaps 5 are folded over in a closed position and released therefrom the said flaps tend to resume their original straight or semi-stiff form. The pouch preferably made to fit the average coat-pocket I shall describe somewhat in detail.

10 Referring particularly to the drawings: I select a suitable, closely and evenly woven or grain material that when cut or blanked to size will measure approximately 5 x 8½ inches to form the part A, Figure 1, having parts—one at each 15 end thereof, extended outwardly from one of the heavy dotted lines, *a2*. The lines *a2* are spaced from opposite sides of the transverse median of the part A. The parts extending outwardly from the lines *a2*, when the pouch is 20 completed, provide integral end flaps, *a4*. Each flap *a4* is formed with spaced perforations, *a1*, for permanently receiving the female members of flap fastener devices.

From the same kind of material I cut or blank 25 therefrom a part that will measure approximately 5 x 6½ inches to form the front part B, Figure 2, having parts, one at each end thereof, extended outwardly from the dotted lines *b2*. The lines *b2* are spaced from the sides of the 30 transverse median of the part B. The parts which extend from the lines *b2* form, when the pouch is completed, integral end flaps, *b4*, which are of materially less length than the flaps *a4*. The part B, inwardly of and in proximity to each 35 dotted line *b2*, is formed with spaced perforations, *b1*, for permanently receiving the male members of flap fastener devices. Secured to the outer face of the upper end flap *b4*, or formed integral therewith, is a hollow strip of 40 material indicated by *b5* which will be mentioned further along.

The part C, Figure 3, is in the form of a wall 45 having a cut-out and is associated in alignment with a portion of the part A to co-act therewith to form a pocket secured at one end and its sides to the inner face of the flaps *a4*, as shown in Figure 4, the said pocket being open at its front end, *c1*, to admit, and change when necessary, a match striking element material or 50 pad exposed for striking use by the cut-out opening *c2* of the part C, readily available for use and reliably protected when the flap, *a4*, is closed, as shown in Figure 11.

The part F, Figure 7, is also preferably rec- 55 tangular in form and is associated in alignment with a portion of the part A to co-act therewith to form a pocket secured at one end and its sides, to the inner face of the flaps *a4*, as shown in Figure 9, the said pocket being open at its 60 front end, *f1*, to admit, preferably, matches readily available for use in connection with the scratch-pad of part C, and in a like manner reliably protected when the flap *a4* is closed as 65 shown in Figure 11, and is especially handy when the compartment is made, for carrying cigars, by the addition of the part D to the pouch.

As a preferred method of procedure a stud or male fastener part is permanently attached to part B through a perforation, *b1*, in its upper 70 right corner. The part B is then placed in position on part A with their side edges coinciding, and the dotted lines *a3* of part A and the flap ends *b3* of part B coinciding in alignment, see Figure 4; then parts A and B are attached or 75 fastened together in any secure manner or by

stitching as indicated by the lines of stitching in Figure 4, thus I make in the pouch a few selected compartments in appropriate size and shape namely: *ab1* for instance for carrying smoking or chewing tobaccos or a package of 5 twenty-cigarettes; *ab2* for carrying a complete pipe or package of ten cigarettes; the placement of a pipe-stem cleaning rod compartment is not limited to the position as seen in Figure 4, *ab4*, outlined by a line of stitching, sufficient for the 10 purpose, run near the edge of the pouch as to form a compartment or holder but showing as a working example a pouch having a compartment carrying my combined rod and spatula pipe stem and bowl cleaner as shown outlined 15 in the holder compartment, *ab4*; the said rod in combination with said integral parts' holder aids in stiffening either side of the pouch where so used, or when placed at either end of the pouch either by making the said cleaning rod 20 holder integral with the flap member *b4* or by attaching the holder as made of a strip of material in the form of a hollow cylinder, *b5*, to the said flap, *b4*, as shown in Figures 2 and 4, and especially in Figure 6, where the, made observ- 25 able, open end of the hollow strip of material at its appearing right outward side is shown as decidedly attached to, or as a part of, the flaps *b4* of the part B and shows the obverse open end of the said cylindrical hollow strip distorted 30 from its hollow cylindrical form to that of an ellipse by the pressure exerted by the fold over closure of the flaps *a4* and *b4* contacting as shown in Figure 6. When the pipe-stem cleaning rod is sheathed as within said hollow cylindrical holder compartment the flattening, as shown in Figure 6, of the cylindrical strip of material, is prevented and the combined pressure against the overfolding flaps is greater, thus firmly closing the pouch exits as between the 35 said flaps. The cylindrical strip of material, *b5*, makes in combination, especially so when carrying the pipe-stem cleaning rod, an extra closing pressure where desired on the contacting 40 surfaces of the flaps *a4* and *b4*, hence being of great utility when the said flaps are closed and fastened as in Figure 11, thus preventing any 45 escapement of the pouch contents, especially in respect to pipe-tobacco and the like.

The compartment *ab3* can be used for snuff, 50 etc., or, if preferred, for carrying the usual package of matches, or a modern lighter.

The remaining studs or male fasteners are 55 permanently attached to part B through the perforations *b1* and the female clasps of the fasteners are permanently attached to part A through the perforations *a1*.

The perforations *a1* and *b1* are in horizontal alignment; the outer perforations *a1* and *b1* from end to end are in vertical alignment but the 60 middle perforations, as through end to end, are not in vertical alignment; this off center placement of the said middle perforations, see Figures 4, 9 and 11, places the pouch fasteners to extra advantage for the purposes intended. 65

It is evident that the part B could be placed upon the part A in a so called upside down position without causing a misfit, as the beforehand punched perforations would line up perfectly as in the off-center placement, as herein- 70 set forth.

The said off-center spacing of the fasteners are shown to advantage in closing the opening of compartment *ab2* in the perfect and ready covering of the flaps and the fastening of same 75

at the top and bottom front line of a pipe bowl when the said compartment is used for carrying a pipe.

The in line fasteners make secure the pipe-
5 stem and bowl cleaner as carried by its holder
ab4, in combination as or when located at either
side or end of the pouch; likewise when the flaps
a4 and *b4* are folded over coincidentally at the
10 dotted lines *a2* and *b2*, and the fasteners *a1* and
b1 are interlined and fastened, their approxi-
mate surfaces contact in such a manner as to
prevent the escapement of any of the contents
15 from compartments of the pouch, see Figures
5, 6 and 11, and 12 further along.

15 An additional compartment part *D*, see Figure
8, is cut or blanked to measure 5 x 6 inches with
each corner notched and each end of part *D* hav-
ing three perforations large enough to fit loosely
20 over the stud parts of the male fasteners of part
B, so as not to interfere with the alignment of
the said stud parts with the closure and clasping
arrangement therewith of the relative female
25 fasteners of the part *A*, nor to prevent the opera-
tions of the full-mouth-openings of the compart-
ment formed by the superimposed part *D* to the
pouch. When the pouch is intended to carry the
30 part *D* to form therewith an extra compartment
the side edges of parts *A* and *B* are not fastened
together until the part *D* has been superimposed
thereon in true alignment position, as shown in
35 Figure 9, at which time the true aligned edges of
parts *A*, *B* and *D* are fastened in an approved
manner or stitched together as shown in Figure
9. When the flaps *a4* of part *A* are folded over
40 to contact with the flaps *b4* of the part *B* and the
female parts of the fasteners, *a1*, fully contact
with the studs, *b1*, the inside contacting, now
curving, parts of the flaps *b4* throughout their
width, are made to firmly contact with and
45 against the entire ends edges, *d3*, of the part *D*;
this full contact over and against the upright
edges *d3* of the part *D* forces a tighter closure of
the flaps, *a4* and *b4*, throughout their contiguous
50 contacting surfaces than would take place with-
out the said full provisions of part *D*, see Figure
8 and Figure 12.

The notches, *d2*, Figure 8, mark limit the stitching
55 or any preferred side fastening together of
the parts *A*, *B* and *D*, along their side edges as
within the bounds of the horizontal borders of the
said notches, *d2*, thus leaving the side edges of
the flaps *a4* and *b4* unfastened and leaving the
outer end edges, *d3*, part *D*, somewhat free for
ready adaptability within and firmly against the
55 apex (see Figure 12) of the inner curving surface
of the flaps *b4* which pressure of said ends, *b3*,
in closing the pouch causes a combined pressure
contacting and a decided closure of the intimate
surfaces of the flaps *a4* and *b4* of the parts *A*
60 and *B*, in conformity and practical, effective com-
bination, and thus practically completing a large,
extra, readily accessible at either end, superim-
posed compartment to the pouch, making the lat-
ter in combination when closed comparatively air
65 tight.

When cigars or other articles are to be carried
70 in the large compartment formed by the addition
of the part *D* to the pouch, cigars, etc., can be in-
serted or removed by opening either end of the
pouch.

The pouch may comprise only one compart-
ment, for carrying cigars, etc., made by placing
part *B*, or part *D*, in position on part *A* and fast-
ening their relative side edges together except the
75 side edges of the flaps thereof, then permanently

attaching the male and female parts of the fas-
teners relative to flap and opposite perforations
as hereinbefore mentioned, and attaching to the
pouch the scratch-pad compartment *C* and match
compartment *F* attached to the pouch flap, *a4*, as
5 shown in Figure 9.

Cigars, etc., can be carried in the large com-
partment without breakage by exercising ordinary
care; to obviate injury to cigars, etc., so carried a
part *E*, Figure 10, to measure 4½ x 5 inches, in 10
proportion to the example size hereinbefore men-
tioned and preferably made from .020 fiber board
and having approximately one-fourth inch han-
dle end extensions or tabs so placed in off center
alignment as not to interfere with the hereinbe-
fore mentioned off center alignment of the pouch
fasteners when the part *E* is inserted within the
large compartment of the pouch. The part *E*
gives added stiffness, and added protection to the
contents as well as surfaces of part *E* to which 20
implements and articles may be removably at-
tached.

It readily may be seen that the pouch, especi-
ally when formed as a combined compartment
pouch, is admirably arranged for carrying at one 25
time the various tobaccos and accessories, or in
separate allotments, as may be desired.

I claim:

1. A pouch having a backing member, a second
member of shorter length than said backing mem- 30
ber positioned on and secured to said backing mem-
ber in such a manner that an end of said
backing member projects, forming a flap, an end
of said second member near said flap being turned
over to form a sheath along an edge thereof and 35
a stiffening member in said sheath, whereby when
said flap is turned over to close the pouch said
stiffening member aids in preventing leakage of
the contents.

2. A pouch having an outer member, an inner 40
member having one dimension less than that of
the outer member, said inner member being se-
cured to and so positioned with respect to said
outer member that the outer member extends be-
yond the inner member and provides a closure 45
flap, a sheath along the edge of the inner member
adjacent said flap and means in said sheath caus-
ing the edge of the inner member normally to lie
closely adjacent to said outer member.

3. A blank for attachment to a backing member 50
in making pouches comprising a generally rec-
tangular member having a row of perforations
therein adjacent each of two opposite edges there-
of, the perforations in each row being non-uniformly
arranged, the arrangement along one edge 55
being similar to but the reverse of the arrange-
ment along the other edge; whereby said blank
may be positioned on the backing member in
either one of two positions.

4. A blank for attachment to a backing member 60
in making tobacco pouches comprising a general-
ly rectangular member of flexible resilient mate-
rial having a row of perforations therein adjacent
each of two opposite edges thereof, the perfora-
tions in each row being non-uniformly arranged, 65
the arrangement along one edge being similar to
but the reverse of the arrangement along the
other edge, whereby said blank may be positioned
on the backing member in either one of two pos-
itions, the corners of said blank being relieved so
70 that the edges do not meet at a sharp angle
whereby the assembly of the pouches is facilitated.

5. In combination with a pouch as set forth in
claim 1, a third member of flexible resilient char-
acter so shaped that it may be readily assembled 75

with the other members, said third member having a row of perforations therein adjacent each of two opposite edges thereof, the perforations in each row being similar to but the reverse of the arrangement along the other edge, projecting members on said second member so positioned as to receive said third member in either of two positions.

6. A blank for attachment to a backing member in making pouches comprising a generally rec-

tangular member having a row of fastener positioning means on one face thereof adjacent each of two opposite edges thereof, the fastener positioning means in each row being non-uniformly arranged, the arrangement along one edge being similar to but the reverse of the arrangement along the other edge; whereby said blank may be positioned on the backing member in either one.

WILLIAM EDWARDS BAXTER. 10
